UNITED STATES PATENT OFFICE.

EDWARD B. PAUL, OF LANCASTER, PENNSYLVANIA, ASSIGNOR TO LANCASTER AUTOMATIC MACHINE COMPANY, OF LANCASTER, PENNSYLVANIA, A CORPORATION OF DELAWARE.

COIN-HANDLING APPARATUS.

1,374,468.

Specification of Letters Patent. Patented Apr. 12, 1921.

Original application filed November 16, 1918, Serial No. 262,767. Divided and this application filed March 28, 1919. Serial No. 285,928.

To all whom it may concern:

Be it known that I, EDWARD B. PAUL, a citizen of the United States, residing at 7 North Duke street, Lancaster, in the county of Lancaster, State of Pennsylvania, have invented certain new and useful Improvements in Coin-Handling Apparatus (Case B;) and I do hereby declare the following to be a full, clear, and exact description of the invention, such as will enable others skilled in the art to which it appertains to make and use the same.

The present invention which relates to coin handling apparatus is directed particularly to mechanism for feeding coins, one at a time to any apparatus in which the coins are to be assorted, counted or otherwise acted upon. This mechanism may be employed in conjunction with the coin assorting and counting apparatus constituting the subject matter of my co-pending application Serial No. 262,767 filed November 16, 1918, of which the present application is a division, or it may be employed in conjunction with any other form of coin handling apparatus in which it is desired that the coins shall be fed, one at a time, to some other part of the apparatus for subsequent disposal.

In accordance with the present invention there is provided a receptacle into which coins may be supplied in quantity and which has an inclined bottom made up of a rotary portion provided with a number of coin receiving pockets and a fixed portion provided with an aperture and also serving as a support for the rotary portion which by its movement over the fixed portion will cause the coin receiving pockets to be brought successively into registration with the aperture in the fixed portion to permit the coins to fall therethrough, one at a time, into the apparatus with which the feeding mechanism is associated. In connection with the receptacle there is a deflector mounted on its rear wall in position to deflect the coins as they fall into the receptacle, so that they will lie flat upon the bottom to insure that they shall be picked up in the pockets as the bottom rotates.

The particular nature of the invention, as well as other objects and advantages thereof, will appear more clearly from the descrip-

tion of a preferred embodiment which is shown in the accompanying drawings in 55 combination with the coin handling mechanism forming the subject matter of my application referred to above.

In these drawings Figure 1 is a side elevation of the entire apparatus, chiefly in section;

Fig. 2 is a front elevation in section along the line 2—2 of Fig. 1;

Fig. 3 is a plan view in section along the line 3—3 of Fig. 1;

Fig. 4 is a plan view in section along the line 4—4 of Fig. 1;

Fig. 5 is a front elevation of parts of the assorting and counter actuating mechanism in section along the line 5—5 of Fig. 1; 70

Fig. 6 is a plan view of the receptacle into which coins are supplied and by which they are fed one at a time into the assorting mechanism;

Fig. 7 is a rear elevation, showing the gear 75 trains for driving various parts of the apparatus, the casing being taken in section along the line 7—7 of Fig. 1; and

Figs. 8, 9, 10, and 11 are detailed views showing different positions assumed by the 80 coin-controlled counter actuating devices, during a cycle of operations of the apparatus.

Referring to the drawings in which similar reference characters denote similar parts 85 throughout the several views, 1 is the casing of the apparatus which should preferably be constructed of metal and upon the top of which is a funnel 2 into which coins may be supplied. The lower end of the funnel is 90 bent at a right angle and communicates with a rotary hopper 3 provided with an aperture at 4, through which coins are discharged when the aperture occupies its lowermost position. The forward end of hopper 3 is 95 movably mounted in a suitable bearing formed in the front wall 5 of the coin feeding mechanism into which the coins fall when they leave the hopper. The rear wall 7 of this mechanism supports at its upper 100 edge a trunnion 8 attached to the closed end of the hopper and carrying a gear 9 meshing with a pinion 10 on an axle attached to the wall 7, and having a gear 11 meshing with a pinion 12 mounted on an axle on the rear 105 wall 7 and having a gear 13 which meshes

with a pinion 14 on a shaft 15 mounted in a partition 16 extending between the side walls of the casing. Associated with the pinion 14 is a gear 17, which, through the 5 train of gears and pinions 18, 19, 20, and 21, is connected to a shaft 22 mounted in a suitable bearing near the bottom of the partition 16. Slidably mounted on the end of shaft 22 is a cup-shaped member 23 adapted to be 10 forced outwardly by a spring 24 surrounding the shaft. The member 23 serves as one part of a clutch, the other member 25 of which is attached to the shaft of a motor 26 suspended from a bracket 27 which, at its 15 upper end, is provided with hooks 28 adapted to fit over pins attached to the rear wall of the casing, the arrangement being such that when the bracket is in place, the weight of the motor will tend to hold the clutch members 23 and 25 firmly in engagement to provide a driving connection between the motor and the moving parts of the apparatus.

The coin feeding mechanism 6 into which 25 coins are discharged from the hopper 3 appears most clearly in Figs. 1 and 6. It comprises a receptacle of oblong contour and considerably shorter at the front than at the back so as to provide for an inclined bottom. 30 This bottom is made up of a lower plate 30 and an upper plate 31, connected together by pins or screws and between which is an annular support 32 attached to the lower edge of the wall of the receptacle. The 35 combined plates 30 and 31 are thus rotatably mounted at the bottom of the coin receiving receptacle, and for imparting rotation to these combined plates, the periphery of the lower plate is provided with beveled 40 gear 33 attached to the inner end of shaft 15 and hence driven by the motor 26. Each of the plates 30 and 31 is provided with registering apertures as at 34 and 35 respectively, of which four are shown in the present case, although any other number may be provided. The annular supporting member 32 is provided with one aperture in its uppermost portion, as at 36, adapted to register with each pair of apertures in the rotary plates as these apertures pass over the upper portion of their path.

As a further refinement of the construction, each aperture in the upper plate 31 55 should be disposed slightly in advance of its corresponding aperture in the plate 30 so that when a coin which has been carried upward in the recess formed by the aperture in the upper plate, reaches the point where 60 the apertures register with the aperture in the annular member, the coin will be tipped over to insure its discharge into the assorting mechanism of the apparatus. Also, in order to permit coins to be easily taken up 65 by the pockets formed by the apertures 34

and the annular plate 32 when these apertures are in their lowermost positions, the edges of the same should be somewhat beveled as indicated at 37 in Fig. 6. Attached to the rear wall 7 of the coin feeding receptacle, is a deflector 38 so constructed as to tip the coins as they fall into the lower part of the receptacle and prevent any of them from remaining on edge against the rear wall 7 with possible clogging of the coins 75 in the receptacle.

The assorting device into which the coins are fed one at a time by the mechanism described above, appears most clearly in Fig. 5 from which it will be seen that it comprises a chute 40 which terminates in a transversely extended, inclined run-way 41 divided into a plurality of coin-receiving pockets 42, 43, 44, 45, and 46, by the coin-engaging projections 47, 48, 49, and 50. In 85 the embodiment shown, the apparatus is adapted to handle half-dollars, quarters, nickels, pennies and dimes, and the first projection 47 is adapted to engage half-dollars, retaining them in the pocket 42 and 90 permitting all other coins to pass beyond. The second projection 48 engages the quarters, retaining them in the pocket 43 and allowing the other coins to pass on. The third projection 49 engages the nickels, retaining them in the pocket 44 and allowing the pennies and dimes to pass on, the former being caught by projection 50 and held in pocket 45 and the dimes passing to the end of the run-way, where they are held in 100 pocket 46.

Each of the coin-receiving pockets is provided with an opening in its bottom through which the coin may pass as hereinafter described. The opening of each pocket is normally closed by means of a gate 51, it being understood that there is a separate gate for each pocket, and that the several gates and their associated parts are of similar construction.

Each gate is composed of a shelf portion 52 and a step portion 53 spaced from the outer edge of the gate and which in the normal position of the gate lies beneath the corresponding opening in the bottom of the 115 coin receiving pocket, as shown most clearly in Fig. 8. Each gate is carried upon a horizontal slide 54 mounted between pairs of transverse supports 55 and 56 extending between the sides of the casing. Each slide is 120 normally drawn forward by a spring 57 fastened at one end to a pin 58 attached to the slide and at the other end to a pin 59 on the upper one of the transverse supports 55. As appears most clearly in the plan view (Fig. 3), each of the slides 54 is cut away or slotted as at 60 to provide a space through which extends a reciprocating bar 61 which, as shown most clearly in Fig. 5, is composed of an upper vertical portion and a 130

lower vertical portion, these portions being connected by a horizontal offset portion so that the lower portion is displaced to one side of the upper portion to bring the former into proper relation to the coin-wrapping mechanism. The upper vertical portion of each bar is guided in slots formed in the transverse supporting members 55, as at 62, and the lower vertical portion of each bar is guided by a transverse member 63.

As shown most clearly in the detail views, Figs. 8 to 11, the upper portion of each bar is provided with a notch 64 having inclined sides of different length, and the bar is narrower above the notch than it is below. The notch is adapted to coöperate with a lug 65 extending from the slide 54, or between the sides of the slot in the slide in those cases where the reciprocating bars pass through slots instead of cut-away portions, as in the case of the slides for controlling the half-dollars and quarters. Pivoted to the top of each bar 61, is a depending swing 66 which is provided with a slot 67 within which is a pin 68 extending from the corresponding slide in alinement with the lug 65. As appears most clearly in Fig. 3, the swings associated with the units for controlling the half-dollars and quarters pass through the slots in the slides 54 of these units, but in the case of the other units, the swings are arranged at one side of the cut-away portions of the slides through which the reciprocating bars pass.

For actuating the bars 61 and swings 66, there are lifts 70 slidably mounted in vertical bearings between the transverse frames 56 and 63. Each lift is provided with a lug 71 adapted to coöperate with a corresponding lug 72 projecting from the rear face of the reciprocating bar. The upper forward edge 73 of the lift is adapted under certain conditions to engage the lower end of the corresponding swing 66 to raise it and the reciprocating bar to which it is attached. Each lift has lugs projectings for its rear face to which is attached a link 74 connected to a crank 75 on a transverse shaft 76 provided near one end with a bevel gear 77 meshing with a pinion 78 on the end of a stub shaft 79 (Fig. 4) which is the one on which the pinion 19 and gear 20 hereinbefore described are mounted. There is thus provided a driving connection from the shaft 22 which is driven by the motor 26 and the shaft 76 by which the lifts are reciprocated in their respective guideways.

The operation of the apparatus is as follows: Coins to be assorted are supplied to the hopper 3, which is rotated through the train of gears connecting it to the shaft 22, it being understood that the motor 26 is running, and the clutch members 23 and 25 are in engagement as shown in Fig. 1. As the aperture 4 in the hopper 3 passes over the lower

portion of its path, coins will be discharged into the mechanism for feeding them one at a time to the coin-assorting devices. The coins in falling into the receptacle of the feeding mechanism will strike the deflector 38 and be turned so as to lie parallel to the rotary base 30, 31 of the feeding mechanism. Since this base is continually driven through the gear 15 associated with the driving gears of the apparatus, the coins lying upon the base 70 will be continually agitated and picked up one at a time in the pockets 34 as the latter pass under the coins. As each pocket carries a coin upwardly, it will finally reach the point where the annular member 32 is cut 75 away at 36, and when this occurs the coin will fall through the aperture into the chute 40 and drop into engagement with one of the projections 47, 48, 49, or 50, on the lower end of the run-way according to its denomination.

The gear train which drives the plates 30, 31 of the mechanism by which the coins are fed one at a time to the assorting apparatus, should preferably be so related to 90 the mechanism for controlling the gates beneath the coin pockets, that the gates are operated in proper timed relation to the discharge of coins into the upper end of the coin chute to allow for the time taken by 95 the coins to fall from the feeding mechanism through the chute to their respective pockets, so that when a coin reaches its receiving pocket, the corresponding slide 54 occupies the position shown in Fig. 8, with 100 the top of the step 53 beneath the pocket, so that the coin rests thereon. At this time the corresponding reciprocating bar 61 occupies the position shown in this figure, being held by the lug 65 which is drawn into 105 the bottom of the notch, and the swing 66 is drawn into the position shown by the slot and pin connection 67, 68. As the lift is drawn downwardly by the rotation of shaft 76, its lug 71 finally engages the coöperating lug 72 upon the reciprocating bar, drawing the latter downwardly into the position shown in Fig. 9. As the bar is drawn downwardly, the shorter face of its notch will through its engagement with lug 55 cause 110 the slide 54 to be retracted into the position shown in Fig. 9 so that the coin will drop from the top of the step 53 onto the shelf 52, but the slide will not be retracted enough to release the coin. As the reciprocating 115 bar is drawn downwardly to retract the slide 54, the pin 68 which lies within the slot 67 of the corresponding swing 66 will swing the latter into the position shown in Fig. 9 so that upon the following upward movement of the lift 70, the upper edge 73 of the latter will engage the lower rear edge of the swing and carry the latter and the reciprocating bar connected to it upwardly. 120 As soon as the reciprocating bar begins to 125 130

rise, the notch therein will release the lug 65 and the slide 54 associated therewith from its retracted position, and the spring 57 will tend to draw the slide forwardly, but such forward movement will soon be arrested by the step 53 coming into engagement with the edge of the coin, thus preventing the lug 65 from following the incline of the notch and holding it in a position with respect to the latter as indicated in Fig. 10. The slot 67 in the swing is so shaped that during the upward movement of the swing and the limited forward movement of the slide until the step engages the edge of the coin, the swing will be held toward the rear with its lower corner above the edge of the lift 70. As long as the swing is in engagement with the lift, the reciprocating bar will be raised, and in the present case this action will continue throughout the entire upward stroke of the lift, but after a slight rise of the reciprocating bar the longer face of its notch will engage the lug 65 and force the latter back to produce a corresponding movement of the slide 54 with the result that when the lift reaches its upper limit of movement, the slide will be retracted enough to remove the gate 51 from beneath the coin, thus allowing the latter to fall out of its pocket into a suitable chute 80 by which it is conveyed to a suitable receptacle, or to mechanism for wrapping the coins.

The shaft 76 is continually driven and the lifts 70 are continually reciprocating, but it is only when a coin is in a pocket that the sequence of operations described above and illustrated in Figs. 8, 9, 10 and 11 will occur. At other times, that is, when there is no coin in a pocket, the corresponding reciprocating bar and its associated slide will normally occupy the position shown in Fig. 8, and when the corresponding lift passes downwardly to draw the bar into the position shown in Fig. 9, the slide will be retracted as above described. When there is no coin resting upon the gate, there will be nothing to prevent the forward movement of the slide to its normal position, so that the lug 65 following the shorter side of the notch will pass to the bottom of the notch as the bar rises, and the corresponding swing 66 will through the pin and slot connection be swung forward enough to draw its lower corner out of engagement with the top of the lift. This action will occur at the time when the lug 65 has reached the bottom of the notch in the reciprocating bar, so that the apparatus comes back to normal position, and the reciprocating bar is not lifted into position shown in Fig. 11, although the lift 70 goes to its upper limit of movement.

Each of the shelves 51 and the mechanism associated therewith will go through

the same sequence of operations, as described above, but owing to the length of the coin run-way, the dimes and pennies will require an appreciably longer time to reach their respective pockets than will the coins of larger diameter. When each of the coins reaches its stop, the corresponding shelf should be in the position shown in Fig. 8, in order to compensate for the different length of the paths over which coins of different denominations have to pass, the cranks 75 are angularly displaced upon the shaft 76 with relation to each other, so that their lifts 70 cause the corresponding reciprocating bars and slides to be operated in proper timed relation to each other.

In the apparatus described above, the rise of the reciprocating bars into the position shown in Fig. 11 is utilized to actuate a register, of the type shown in my copending application Serial No. 262,767, and also to control the operation of wrapping mechanism such as is shown in that application, and which also forms the subject matter of a copending divisional application Serial No. 285,929 filed Mar. 28, 1919.

The register is mounted in the upper front part of casing 1 and comprises a casing within which are counters adapted to be actuated by gears which in turn are operated by arms mounted upon a common shaft and arranged with their inner ends lying in the paths of the reciprocating bars. Since the complete details of this registering mechanism are included in the subject matter of my copending application Serial No. 262,767 they will not be further described herein.

The wrapping mechanism mounted in the bottom of casing 1 comprises a number of units each adapted to wrap coins of a particular denomination, which are supplied through a chute 80 from the corresponding coin pocket of the assorting and counting mechanism. Each unit of the wrapping mechanism comprises a series of receptacles adapted to hold wrappers into which coins may be supplied one at a time as they are discharged from the assorting and counting mechanism. When a predetermined number of coins have been deposited in a wrapper the receptacles are advanced to bring an empty wrapper into position to receive coins. The mechanism for controlling the advance of the receptacles is adapted to be actuated by the corresponding reciprocating bar 61 as it goes to its upper limit of movement due to the presence of a coin in the pocket, so that for each coin counted an actuation of a moving element of the wrapping mechanism takes place, and when a number of such actuations corresponding to the number of coins to be supplied to each wrapper, has occurred, the moving element acts to advance the receptacles to

bring an empty wrapper into position to have coins supplied thereto. Associated with each unit of the wrapping mechanism is a device for crimping the ends of the 5 wrappers after they have been filled with coins, and this device is also operated by the upward movement of the corresponding reciprocating bar 61. This wrapping and crimping mechanism is described in 10 detail in my copending applications Serial Nos. 262,767 and 285,929 and therefore will not be further described herein.

I claim:

1. Apparatus for feeding coins to a coin-handling mechanism, comprising a receptacle into which coins are supplied, a movable bottom for said receptacle provided with coin-receiving pockets, a fixed bottom portion provided with an aperture of substantially the same size and shape as the pockets, and means for moving said movable bottom portion to bring said coin-receiving pockets successively into register with said aperture to permit a coin to fall therethrough and be discharged from the feeder.

2. Apparatus for feeding coins to a coin-handling mechanism, comprising a receptacle, a rotatable bottom for said receptacle provided with coin-receiving pockets, a fixed annular bottom portion upon which said rotatable bottom is supported, said annular bottom portion being provided with an aperture of substantially the same size and shape 35 as the pockets, and means for rotating said rotatable bottom portion to bring the coin-receiving pockets therein successively into register with said aperture to permit a coin to fall therethrough and be discharged from 40 the feeding apparatus.

3. Apparatus for feeding coins to a coin handling mechanism, comprising a receptacle having a fixed vertical wall and an inclined circular rotary bottom provided 45 with a plurality of coin receiving pockets, the outer portions of which lie adjacent to the fixed wall, an inclined fixed annular bottom portion upon which said rotatable bottom is supported, said fixed bottom portion being provided with an aperture in its 50 upper part, and means for moving the said rotatable bottom to bring the coin-receiving pockets therein successively into register with the aperture to permit coins to fall 55 therethrough and be discharged from the feeding apparatus.

4. Apparatus for feeding coins to a coin-handling mechanism, comprising a recep-

tacle, a movable bottom for said receptacle formed of a pair of circular plates connected to each other, an annular member extending between the circular plates and upon which said plates are rotatably mounted, said circular plates being provided with registering apertures on opposite sides of the annular member, the apertures in the upper plate forming in connection with the annular member coin-receiving pockets, said annular member being provided with an aperture in the path of the registering apertures in 70 the plates, and means for rotating said plates to cause the apertures therein to successively coincide with the aperture in the annular member to permit coins to fall from the pockets. 75

5. Apparatus for feeding coins to a coin-handling mechanism, comprising, a receptacle, an inclined rotary bottom for said receptacle provided with a plurality of coin receiving pockets, an inclined fixed annular bottom portion upon which said rotatable bottom is supported, said fixed bottom portion being provided with an aperture in its upper part, means for rotating said rotatable bottom to bring the coin-receiving pockets 85 therein successively into register with the aperture to permit coins to fall therethrough and be discharged from the feeding apparatus, and means mounted on the rear wall of the receptacle to cause coins to be deflected 90 so that they lie flat upon the movable bottom in position to fall into the pockets therein as the latter pass under the coins.

6. Apparatus for feeding coins to a coin handling mechanism, comprising a receptacle, a movable bottom for said receptacle formed of upper and lower circular plates connected together, an annular member extending between the circular plates and upon which they are rotatably mounted, said circular plates being provided with coöperating apertures on opposite sides of the annular member, the apertures in the upper plate being disposed slightly in advance of the corresponding apertures in the lower plate, 100 and forming in connection with the annular member coin-receiving pockets, said annular member being provided with an aperture in the path of the coöperating apertures in the plates, and means for rotating the plates to 105 cause the coöperating apertures therein to successively coincide with the aperture in the annular member to permit coins to fall from the pockets. 110

In testimony whereof I affix my signature. 115
EDWARD B. PAUL.
